UNITED STATES PATENT OFFICE.

GUSTAV BERNHARD PETSCHE, OF PHILADELPHIA, PENNSYLVANIA, AS-
SIGNOR TO SOUTHWARK FOUNDRY & MACHINE COMPANY, OF PHILA-
DELPHIA, PENNSYLVANIA, A CORPORATION OF PENNSYLVANIA.

PUMP.

No. 850,248.

Specification of Letters Patent.

Patented April 16, 1907.

Original application filed April 22, 1903, Serial No. 153,775. Divided and this application filed May 11, 1904. Serial No. 207,379

To all whom it may concern:

Be it known that I, GUSTAV BERNHARD PETSCHE, a subject of the Emperor of Germany, residing in the city and county of Philadelphia, in the State of Pennsylvania, have invented a certain new and useful Improvement 5 in Pumps, of which the following is a true and exact description, reference being had to the accompanying drawings, which form a part thereof.

My invention relates to a novel device for actuating the delivery-valves in pumps having sliding gridiron valves, and is especially adapted or intended for use in connection 15 with blowing-engines or compressors.

In my Patent No. 784,122, granted March 7, 1905, on an application copending with this I have shown and described the delivery-valve-actuating mechanism which in its broad features is similar to my present invention, and in my other application for Letters Patent, filed April 22, 1903, Serial No. 153,775, of which this case is a division, I have shown and described the same mechanism, but only claim 25 it in a particular combination with the mechanism for actuating the admission-valves.

The nature of my present improvements will be best understood as described in connection with the drawings in which they are 30 illustrated, and in which—

Figure 1 is an end view of the compressing-cylinder of the blowing-engine with the receiver-cover removed and the actuating-cylinder which opens the delivery-valve shown 35 in central longitudinal section, and Fig. 2 is a diagram illustrating the operation of the mechanism for closing the delivery-valve.

J indicates the compressing-cylinder of the blowing-engine, having admission-ports (indicated at k) and admission-valve, (indicated at K,) situated on the inner sides of these admission-ports.

l indicates the delivery-ports of the engine, and L the gridiron delivery-valve working on the outside of these ports, L' being the valve-stem.

J' represents the receiving-chamber of the engine, the outer cover of which, normally bolted to the flange J³, is removed to show 50 the valve.

J² indicates a connecting-pipe connecting each end of the receivers with each other and with the common take-off pipe.

I indicates the piston-rod of the compressing-piston, and G¹⁰ a constantly-rotating 55 shaft driven by the engine through gears G⁹ and G⁸ and shaft G².

T is a piston secured to the valve-stem L' and having projecting from its outer face the hollow cylindrical extension T'. The piston 60 T moves in a valve-actuating cylinder (indicated at U) which has its front or inner end connected through a conduit U⁵ with the pump-chamber J, as is usual in this class of blowing-engines, whereby actuating fluid is 65 admitted to the inner end of the cylinder U from the corresponding end of the compression-cylinder and exhausts over back as the pressure in the compression-cylinder varies. The outer head U' of the valve-actuating cylinder 70 is formed with a cylindrical extension U² of smaller diameter than the cylinder U and in which fits the hollow cylindrical extension T' of the piston T.

U⁴ indicates a choke or non-return device 75 communicating through the outer head U' with the interior of the cylinder U.

U³ is the valve-closing slide, made, preferably, as shown, in the form of a hollow cylindrical piston fitting in the cylindrical extension T and carrying a pivot-pin U⁶, to which is connected one end of the link V⁴. The other end of the link V⁴ is pivoted to an oscillating arm V², which is secured on a rock-shaft V', supported on brackets (indicated at 85 V) and extending out from the edges of the cylindrical portion U² of the cylinder-head. The rock-shaft V' has also secured to it a lever-arm V³, to the end of which is connected one end of a link Z, the other end of which is 90 secured by an eccentric-ring to an eccentric G¹², secured to and moving with the shaft G¹⁰.

The operation of the above-described mechanism is easily followed. The delivery-valve is closed when the compressing-piston 95 begins its motion toward the valve and is opened by the action of fluid under pressure admitted to the actuating-cylinder U from the compressing-cylinder through the conduit V⁵ so long as the delivery-valve is held 100 to its seat by pressure in the receiver of the engine materially in excess of that in the blowing-cylinder. The friction between the valve-seat and valve will prevent the latter from moving. The valve moves, however, 105 with great rapidity when the pressures upon

its face and back become approximately equal, as the pressure in cylinder U can then promptly actuate the piston T, connected to said valve. At the close of the compressing 5 stroke of the piston the eccentric G¹², through the connecting-rod Z, lever V³, rock-shaft V', crank-arm V², and connecting-rod V⁴, acts upon the slide U³, pushing it inward against the end of the piston T and moving the valve 10 to a closed position. The connection of the connecting-rod V⁴ and the oscillating movement imparted to the arm V² are such that in moving from the position indicated in full lines in the diagram Fig. 2, which position is 15 that in which the valve is edge and edge in closing, to the position in which the arm V² is horizontal the valve will simply move over its lap. The further downward movement of the arm V² will in no wise affect the position 20 of the valve, nor is it affected by the upward movement of the arm, which after passing the horizontal position retracts the closing-slide and acts simply to shift it out of the way and leave the valve free to move under the influence of its actuating-cylinder, 25 while the succeeding downward movement will act, as before, to close the valve. The choke-conduits (indicated at U⁴ and u⁴) are provided for the purpose of cushioning the outward movement of the actuating-piston both 30 with regard to the rear side of the actuating-cylinder and with regard to the closing-slide, which in a blowing-engine will not always be retracted to its full extent when the valve is 35 opened.

In my said Patent No. 784,122, of March 7, 1905, I have described and shown mechanism for closing the delivery-valve generally similar to that hereinbefore described, except 40 that the closing-slide is connected by means V⁴ with a slide reciprocating in a straight line. The particular feature of improvement in my present construction lies in utilizing the swinging arm V² in the place of

the reciprocating slide, and with the result 45 that I obtain in this modification or improvement a more rapid retraction and advance of the valve-closing-slide features, which in rapidly-running engines are of considerable practical importance.

Having now described my invention, what I claim as new, and desire to secure by Letters Patent, is—

1. In a pump, a delivery-valve in combination with intermittently-acting means acting with a yielding pressure to open said valve at a time in the motion of the compressing-piston when the pressure in the pump-cylinder and receiver are about equal, a positively-actuated oscillating shaft V', an arm V², secured to said shaft, a slide, and a connecting-rod V⁴, connecting said slide and the arm V², said slide being arranged when moved in one direction, to act on the valve to close it, and when moved in the other direction, to leave the valve free to open under the action of the intermittently-acting device aforesaid.

2. In a pump, a delivery-valve, in combination with a valve-actuating cylinder U, having a cylindrical extension from its outer head and a choke-conduit opening from its outer end, a piston T, connected with the valve and having a hollow cylindrical extension T', fitting in the cylindrical extension 75 from the rear head of the cylinder, a valve-closing slide U³, fitting and moving in the extension T', of the piston and supporting a pivot U⁶, a positively-actuated oscillating arm V³, a link V⁴, connecting said arm with the pivot U⁶, and means for admitting and exhausting actuating fluid to and from the inner end of the cylinder U.

GUSTAV BERNHARD PETSCHE.
